UNITED STATES PATENT OFFICE

JAMES S. MILLER, OF TRENTON, NEW JERSEY

TOWEL HOLDER

Application filed August 16, 1930. Serial No. 475,699.

This invention relates to towel holders and more particularly to a holder for paper towels used to cover the head-rests of dental chairs.

The main object of the invention is to provide a simple and convenient towel holder which can be attached to a wall or be kept in a cabinet drawer and wherein the towels can easily be removed and replaced.

Another object of the invention is to provide means in the holder for giving the towels a permanent curve as they are individually removed.

Still another object of the invention is to provide resilient means for compressing the stack of towels and still allowing same to be removed without being torn.

With the above and other objects in view, as will be presently understood, the invention consists in general of certain novel details of construction and combinations of parts hereinafter fully described, illustrated in the accompanying drawings and specifically claimed.

Fig. 1 is a perspective view of the towel holder shown in a cabinet drawer.

Fig. 2 is a perspective view of the holder support.

Fig. 3 is a view of the movable plate.

Fig. 4 is a bottom view of the towel holder with the support removed.

Fig. 5 is a perspective view of the towel holder shown in a vertical position for being attached to a wall.

Fig. 6 is a section on line 6—6 of Fig. 5.

Fig. 7 is a section on line 7—7 of Fig. 5.

Fig. 8 is a diagrammatic view showing a head-rest of a dental chair covered with one of the paper towels.

In Fig. 1 the towel holder 1 is shown in an inclined position resting in a drawer 2 of a cabinet, while in Fig. 5 the towel holder is shown in a vertical position. In the back of the cabinet is a slot 3 adapted to engage with a hook which may be fastened to a wall.

The towel holder comprises a casing 4 hav-

ing a flat back 5 and provided with a bent over flange 6 at the top. The front of the casing is formed with bent over flanges 7 which provide bearing surfaces for the horizontal bar 8. Attached to the horizontal bar 50 as best seen in Fig. 7 is a flat spring 9 bearing against the movable plate 10. The space between this movable plate and the back 5 of the casing is the magazine or compartment 11 for holding the paper towels 12. 55

At the bottom of the compartment is a triangular shaped stop 13 on which rests the bottom edge of the towels 12. This stop also acts as a bearing surface for the lower edge of the plate 10. The top of the plate 10 is 60 formed with a bent over lip 14 bearing against the stack of towels. To insert a fresh stack of towels the bar 8 and the attached spring 9, and the movable plate 10 are 65 removed from the casing. The towels are then inserted in the magazine and the plate 10 and bar 8 replaced as shown in Figures 1 and 5. As the thickness of the stack of towels is 70 gradually lessened the plate 10 will move towards the towels due to the action of the spring 9 and keep them under constant compression.

It is very desirable to have the towels fit snugly around the head-rest of a dental chair so as to keep the hanging end thereof out of 75 the way of the patient's neck or back. To bring about this result the device is so arranged that the towels are given a permanent curve when pulled out of the magazine so it will hug the head-rest. As previously 80 stated the lip 14 of the plate 10 always bears against the stack of towels due to the resilient action of the spring 9. Now when a towel is pulled out of the magazine the friction of the edge of the lip 14 bearing against the towel will cause the towel to curl. The pull of the towels will be in a downward direction as the flange 6 covering the curvature of the towels will make it unhandy for 85 the towels to be pulled out in an upward 90

direction. The device is purposely arranged so that the towels are pulled out with a downward movement so that a more degree of curl can be had that way.

5 As noted diagrammatically in Figure 8 numeral 15 designates the head-rest of a dental chair, numeral 16 the forward end of the towel and 17 the curved end thereof. It will be noted how the towel hugs the bottom of the head-rest and is out of the way of the patient.

10 For using the towel holder in connection with a drawer as shown in Figure 1 it is desirable that the device be positioned at an angle so the towels can be conveniently pulled. To retain the holder at the proper angle a support 18 is provided. The upper end 19 of the support is adapted to fit into a slot 20 at the bottom of the magazine formed by the bent over portions 21 and the bottom 22 of the magazine. The lower end of the support is bent forming a base 23 for the support.

15 It will thus be seen that I have provided a simple and efficient towel holder made of relatively few parts and which is relatively inexpensive to manufacture. The towels can easily and simply be replaced or removed from the magazine. As they are removed 20 they are automatically given a curl so they will fit snugly around the head-rest of a dental chair. The support 18 is removably fastened to the bottom of the casing. When the towel holder is supported in a vertical position, for instance from a wall, as shown 25 in Figure 5, the support is not used but when the towel holder is kept in a drawer as shown in Figure 1 the support is attached to the casing.

30 40 It is obvious that many minor changes may be made in the form and arrangement of the invention without departing from the material principles involved. I do not, therefore, desire to confine my invention to the 45 exact form herein shown and described but I do desire to include all forms which properly come within the scope claimed.

Having described my invention, I claim:

1. In a towel holder of the class described, 50 the combination of a casing having a flat back, of a movable plate in said casing, the upper edge of said plate being bent inwardly at an angle, the space between the movable plate and said back forming a magazine for 55 a stack of towels, a spring for keeping the bent over edge of said movable plate against the stack of towels, and a triangular shaped stop at the floor of said casing, the lower edge of said plate bearing against said stop.

60 2. In a towel holder of the class described, 65 the combination of a casing having a bent over top and a flat back, of a movable plate in said casing, the upper edge of said plate being bent inwardly at an angle, the space between the movable plate and said back

forming a magazine for a stack of towels, and a spring for keeping said bent over edge of said movable plate against said stack of towels.

3. In a towel holder of the class described, 70 the combination of a magazine for a stack of towels, of means for keeping said towels pressed against each other and means for giving the towels a curl as they are extracted from the magazine, said means including a 75 plate having an inturned edge resiliently bearing against said towels.

80 In testimony whereof I affix my signature.
JAMES S. MILLER.
